UNITED STATES PATENT OFFICE.

WILLIAM J. TREMAIN, OF MINNEAPOLIS, MINNESOTA.

VALVE MECHANISM FOR LOCOMOTIVES.

1,209,907.

Specification of Letters Patent. Patented Dec. 26, 1916.

Application filed January 19, 1916. Serial No. 73,046.

To all whom it may concern:

Be it known that I, WILLIAM J. TREMAIN, a citizen of the United States, residing at Minneapolis, in the county of Hennepin and 5 State of Minnesota, have invented a new and useful Improvement in Valve Mechanisms for Locomotives, of which the following is a specification.

This invention relates to improved valve 10 mechanism for effectively lubricating the pistons in locomotive and other cylinders and the valves which control the ingress and egress of steam to and from the valve chambers.

15 The primary object of this invention is to accomplish this result automatically by the use of the exhaust or waste steam and oil egressing through the exhaust outlet of the steam cylinder which usually operates the 20 air pump.

A further object is to cushion the reciprocating parts of the engine when the steam is shut off and the locomotive drifting and to obviate the manual operation of the throttle 25 for drifting.

To these ends my invention comprises the features of construction and combination of parts hereinafter more particularly described and claimed.

30 In the accompanying drawing forming part of this specification, Figure 1 is a plan of my invention, partly in section, the drawing being of a diagrammatic nature; Fig. 2 is a front elevation of a detail of the locomotive showing my invention applied thereto, part of the drawing being shown in section and diagrammatically and the section of the valve being taken on the line X—X of Fig. 1 when the valve is in lowermost 35 position, Fig. 3 is an enlarged section of a detail of the valve mechanism forming part of my invention, the line of section being taken on the line Y—Y of Fig. 2 when the valve is in superior position and Fig. 4 is a 40 sectional detail of the valve interposed between and within the pipe connecting the air chambers, the valve being illustrated in exhausting position.

In the drawing A indicates a portion of a 50 boiler of a locomotive, B—B the usual main cylinders, C—C the usual steam or valve chests of said cylinders in which the usual valve mechanism not illustrated is employed, D—D the usual steam ducts entering said 55 steam chests from the boiler or the superheater, which is commonly employed, E—E

the air tanks and F the air pump, which automatically maintains the air at constant predetermined pressure in the usual manner, said air pump being operated by the usual 60 steam operated auxiliary power cylinder G, in which a piston not illustrated is reciprocated in the usual manner by live steam received through the inlet 2. This invention 65 contemplates lubricating the valves in the steam chest C—C by the exhaust steam and oil from the power cylinder G and transmitted to the steam chests by means of the supply pipe 3, valve 4, branch pipes 5 and 6, and connecting pipes 7 and 8, the latter being 70 tapped into the opposite end of each of the steam chests.

The valve 4 is in the form of a piston, which is adapted to slide in a cylindrical casing 9, and is provided with a stem 10 projecting upwardly and sliding through a cap 11, on the casing 9. The lower portion of the valve is formed with a cylindrical downwardly extending body 12, which works in a corresponding cylindrical extension 13 to the 80 casing 9, said extension 12 being provided with a packing ring 14 to produce a steam tight slideable joint between the extension 12 and the inner surface of the cylindrical casing extension 13. Live steam is admitted 85 from one of the supply ducts D into the lower end of the cylindrical casing extension 13 below the piston extension 12 by means of the pipe 15, thereby providing means for forcing the piston 4 upwardly into superior 90 position when the throttle of the locomotive is opened and live steam enters the steam chests C—C. A coil spring 16 placed around the stem 10 and held in the cap 11 of the casing presses downwardly upon the valve 95 4 and tends to hold the latter down in lowermost or normal position. When the locomotive is operating under live steam, the valve is raised into superior position and a passage 16' therein, (see Fig. 3), forms a 100 communication through ports 17 and 18, in the wall of the valve chamber with the exhaust pipe 3 (see Fig. 1) and the outlet pipe or duct 19, which is connected with the smoke chamber of the locomotive and leads 105 to the outer atmosphere. The exhaust steam charged with lubricating oil is therefore conducted from the steam cylinder G to the outer atmosphere and there is therefore no back pressure upon the piston in cylinder G caused by the contents of the steam chests C—C when the steam chests are operating

under live steam. When the locomotive is drifting, that is operating freely with the live steam cut off by the throttle, the spring 16 forces the piston valve 4 downwardly into the lowermost or normal position as illustrated in Fig. 2, the port 18 thereby being closed and a passage 20 in the piston valve caused to register with the set of three ports 17, 20' and 21 leading from the exhaust outlet of the steam cylinder G of the air pump and causing the exhaust therefrom to be conducted through the pipes 5 and 6 into the steam chests C—C and thereby lubricating the valves in said steam chests and the inner walls of the cylinders C—C with the oil in said exhaust. The air pump F is connected by the pipe 23 with the air reservoir chambers E—E in which air is maintained at sufficient pressure for the various uses for which air is employed on the locomotive, and train, in the usual manner.

The equalizing pipe connection 24 between the air chambers E—E is provided with an escape valve 25, which is opened and closed by the lever 26. This lever 26 is connected by the link 27 with an arm 28, which is tiltingly mounted between its ends on the support 29, one end of said arm opposite that end to which the link 27 is connected being movably attached to the upper end of the valve stem 10. These parts are arranged, so that when the valve 4 is in normal or lowermost position the vent valve 25 is opened to allow the escape of a small amount of air from the air chambers E—E, thereby causing the automatic pump F to be operated slowly and never stopping. In this manner lubricating oil is always fed into the valve chambers C—C, when the locomotive is drifting or at a standstill and when the throttle is closed.

When the locomotive is drifting or at rest, this lubricating exhaust escapes to the outer atmosphere through the exhaust channel and usual relief valves leading from the steam chests through which the exhaust from the cylinders of the locomotive normally passes into the smoke chamber of the locomotive or to the outer atmosphere. The lubrication received from the oil which egresses with the exhaust and waste steam from the steam cylinder of the air pump is sufficient to at all times lubricate the valves in the steam chests of the engine cylinders B—B effectively. When drifting, it will be observed the waste steam admitted from the air pump cylinder cushions the reciprocating parts in the cylinders B—B and valve chests C—C. Check valves 30 and 31 in the pipes 5 and 6 prevent at all times any steam escaping backwardly through said pipes. Should the throttle leak and back pressure of steam form in the valve chambers on the cylinders B—B the steam leaking from the throttle will pass down the pipe 15 and force

the piston valve 4 up causing the passage 16' to register with ports 17 and 18, thus forming a duct for the waste steam from cylinder G to the outer atmosphere, the same as when the locomotive is operating under steam. The invention therefore is automatic at all times and requires substantially no attention on the part of an attendant.

It will be observed that by the use of my invention a heretofore waste product, *i. e.*, the exhaust steam and oil from the air pump cylinder, is utilized for a useful purpose.

This invention is applicable for use in connection with steam, water and air supply systems and for any other purpose desired and where the term "steam" is used throughout the claims following it is intended to include these other mediums as equivalents. The valve 4 can also be operated by any means desired and for any purpose in which the waste medium from a steam or other pump is utilized for lubricating or other purposes.

In accordance with the patent statutes, I have described the principles of operation of my invention, together with the apparatus which I now consider to represent the best embodiment thereof, but I desire to have it understood that the construction shown is only illustrative, and that the invention can be carried out by other means and applied to uses other than those above set forth within the scope of the following claims.

Having described my invention, what I claim as new and desire to protect by Letters Patent is:

1. In combination with a locomotive and its boiler, main cylinder and a duct for the admission of steam from the boiler to the main cylinder, an auxiliary cylinder having an exhaust through which spent steam and lubricating oil are expended, means for conducting said waste steam and oil into said main cylinder for lubricating the same, valve mechanism for controlling the supply of said expended lubricating oil and steam, and means actuated by the admission of steam from the boiler to the main cylinder for operating said valve mechanism to automatically govern the admission of the lubricating supply to said main cylinder.

2. In combination with a main cylinder and its piston and valve chest, an auxiliary cylinder having an exhaust through which spent steam and lubricating oil therefrom are expended, means for conducting said waste steam and oil into one of said ports for lubricating the same, valve mechanism for controlling said supply of said expended steam and oil, and means for automatically operating said valve mechanism to shut off said lubricating supply when said main cylinder is operating under steam pressure.

3. In combination with a locomotive and

its main steam cylinders, valve chambers for said cylinders having steam supply ducts and air pump operating cylinder having an exhaust outlet for spent operating medium and waste lubricating oil, a passage leading from said exhaust outlet into said valve chambers for conducting said waste medium and oil for lubricating purposes into said valve chambers, a steam valve interposed in said duct and having operative connection with said steam supply ducts to automatically shift said valve and close the supply of waste medium and oil into said chests when the main cylinders are operating under steam pressure and permitting the valve to open said duct and admit said medium and oil into said chests when the supply of live steam is cut off from said chests and the locomotive is drifting.

4. In combination with a locomotive and its main steam cylinders, valve chambers for said cylinders having steam supply ducts, an air pump having an operating cylinder provided with an exhaust outlet for spent operating medium and waste lubricating oil, and an air supply tank maintained under a substantially steady air pressure by said air pump, a passage leading from said exhaust outlet into said valve chambers for conducting said waste medium and oil for lubricating purposes into said valve chambers, a steam valve interposed in said passage adapted in one position to connect said exhaust outlet with said valve chambers and in another position to close said connection and complete

a passage from said exhaust outlet to the outer atmosphere, said valve being connected with live steam supplied to said main cylinders and adapted to be urged into a position admitting said waste oil into said chests, a spring against which said valve is urged under steam pressure and adapted to return the valve, and an escape valve arranged when open to permit the escape of air from said tank, so that the air pump cylinder is continuously operated to supply waste oil to said chests when the locomotive is at rest or drifting, said waste valve being operatively connected with said main valve to operate simultaneously therewith.

5. In combination with a locomotive and its boiler, a main cylinder and a duct for the admission of steam from the boiler to the main cylinder, an auxiliary cylinder having an exhaust through which spent steam and lubricating oil are expended, means for conducting said waste steam and oil into said main cylinder for lubricating the same, valve mechanism for controlling the supply of said expended lubricating oil and steam, and means actuated by the cutting off of the steam supply from the boiler to the main cylinder for operating said valve mechanism to automatically govern the admission of the lubricating supply to said main cylinder.

In testimony whereof, I have signed my name to this specification.

WILLIAM J. TREMAIN.
